UNITED STATES PATENT OFFICE

WILLIAM H. NUTT, OF BEVERLY, MASSACHUSETTS, ASSIGNOR TO UNITED SHOE MACHINERY CORPORATION, OF PATERSON, NEW JERSEY, A CORPORATION OF NEW JERSEY

METHOD OF COVERING HEELS

Application filed January 24, 1929. Serial No. 334,716.

This invention relates to improvements in methods of covering heels. The invention is herein illustrated in its application to the covering of a Cuban heel with a one-piece cover the ends of which meet at the middle of the heel breast, although the invention is by no means limited to the covering of heels of that type or to the covering of heels with a single piece of covering material.

It is a common practice to cover the rear, side and breast surfaces of a Cuban heel with a one-piece cover the opposite end portions of which are overlapped at the middle of the breast face of the heel. This practice results in the formation of an objectionable bulge or ridge in the covered breast face where the meeting end portions of the cover overlap, a condition which detracts from the appearance of the finished heel.

One object of the present invention is to facilitate the formation of a smooth, flush joint between meeting portions of a heel covering.

With this object in view, the invention, in one aspect, provides an improved method of covering heels which comprises overlapping two portions of a heel covering upon a heel surface to be covered thereby, and cutting diagonally through both cover portions while said portions remain overlapped to form on said cover portions beveled edge faces transversely disposed at the same inclinations to the adjacent portion of the heel cover surface and adapted to be neatly fitted together so as to form a flush joint. Preferably and as illustrated, the trimming is effected by a single progressive cutting operation, for example, by a single stroke of a knife, the knife being drawn across the overlapped cover portions so as to form simultaneously two trimmed edge faces which lie in the same plane. As illustrated the trimming cut extends longitudinally in a direction heightwise of the heel and it is inclined in a direction widthwise of the heel breast. Thus skived or beveled edges are produced which are disposed relatively to one another so that the edge faces will over-

lap when the cover portions are brought together without causing any bulge or ridge to be produced at the joint. Moreover, as illustrated, the direction of transverse inclination of the trimming cut is inwardly (i. e., toward the heel breast) and away from the edge of the outermost cover portion, inasmuch as this construction enables the trimmed edges subsequently to be brought together without the necessity of stretching either portion of the cover thereby avoiding any tendency of the joined cover portions later to become separated and the joint to become opened up because of shrinkage of the cover material. After the end portions of the cover have been trimmed as above described, the waste material produced by the trimming operation is removed and the trimmed edges are coated with adhesive, preferably a non-elastic adhesive such as celluloid cement, and pressed firmly together so as to form the desired smooth, flush joint.

The invention will now be more particularly described by reference to the accompanying drawings and thereafter defined in the claims.

In the drawings,

Fig. 1 is an elevational view of a Cuban heel in the process of being covered, the heel being positioned with its breast face directed toward the observer and the figure illustrating particularly the improved method of trimming the meeting portions of the cover;

Fig. 2 is a fragmentary sectional view on an enlarged scale taken along the line II-II of Fig. 1;

Fig. 3 is an elevational view similar to Fig. 1 but illustrating a further step in the trimming of the meeting portions of the cover;

Fig. 4 is a fragmentary sectional view of a heel illustrating the manner of applying adhesive to the trimmed edges of the heel cover; and

Figs. 5 and 6 are fragmentary sectional and perspective views, respectively, of a finished heel covered in accordance with the improved method herein disclosed.

Referring to the drawings, there is shown in Fig. 1 a wooden Cuban heel H to which a one-piece cover C has been applied in the usual way, the cover extending around and entirely covering the rear, side and breast surfaces of the heel and being held in place by suitable adhesive such as rubber cement or other elastic and slow drying adhesive. The heel H may be supported during the heel covering operation, as herein shown, by means of clamping jaws 10 and 12 arranged to engage respectively the seat face s and the top lift-engaging face t of the heel. The cover C is shown in Figs. 1 and 2 as it appears immediately after it has been wrapped around the heel, the lateral margins of the cover projecting beyond the seat and top lift-engaging faces s and t, respectively, in position to be subsequently laid against these faces, and the opposite end portions of the cover being overlapped at the middle of the heel breast and temporarily held firmly together by means of the adhesive initially applied to the cover.

In order to provide for the formation of a flush joint between the meeting end portions of the cover C, these cover portions are trimmed, as herein illustrated, in such a way as to cause the trimmed edge faces to lie in the same plane and to be similarly disposed angularly with respect to the adjacent portions of the heel breast surface. To this end, a trimming tool, such for example as the knife 14 (Figs. 1 and 2), is drawn across the heel cover after being positioned substantially in the longitudinal and transverse angular relation to the heel shown in Figs. 1 and 2, with the cutting edge of the knife extending in a direction heightwise of the heel breast substantially over the middle of the overlapping portions of the cover. Preferably the knife is first presented to the heel with its cutting edge engaging the cover in a location indicated by the dotted line x in Fig. 1 the more accurately to gage the location of the trimming cut. Thereafter the knife may be tilted more or less to bring it into the longitudinally inclined position shown in Fig. 1 so that as the knife is drawn across the cover it will act simultaneously upon both the outer and inner overlapping cover portions, cutting through them to the breast surface of the heel to form the trimming cut indicated at y in Fig. 3. Thus, as the knife is moved along the heel breast it trims the opposite end portions of the cover from the top to the bottom of the heel breast in a single progressive trimming operation. As shown, the trimming knife 14 is also inclined transversely (with respect to its direction of movement) as shown in Figs. 1 and 2, so that the trimming cut will be inclined transversely in a direction widthwise of the heel breast. As a result of this transverse angular relation of the knife

blade relatively to the heel breast, the trimmed edges of the cover are skived or beveled, as illustrated in Fig. 2, and as shown at 16 and 18 in Fig. 4. Moreover, the beveled edges of the inner and outer cover portions will be relatively disposed so that the trimmed edge of the outer end portion of the cover will extend in the same angular relation to the breast surface of the heel as the trimmed edge of the inner end portion of the cover. Thus when the two beveled edges are brought together they will fit one against the other. Also, as shown, the direction of transverse inclination of the trimming knife is inwardly (i. e., toward the heel breast) and away from the edge of the outer overlapping end portion of the cover, thereby causing the beveled edges to be so located transversely relatively to each other as to avoid any necessity for stretching either cover portion in order to fit together the trimmed edges, as will be hereinafter more fully explained.

In order to extend the trimming cut through the unsupported margins of the cover which extend beyond the seat and top lift-engaging faces of the heel, the knife 14, after being drawn across the heel breast as described, may then be drawn successively across the projecting cover margins in such a way as to flatten them against the seat and top lift-engaging faces of the heel, and thereafter to cut through them to the surface of the heel, thus completely severing from the heel cover the material partially separated therefrom by the cut initially made across the heel breast. To facilitate the laying of the cover margins against the seat and top lift-engaging faces of the heel without danger of overlapping the adjacent end portions of the cover, it may be desirable to continue the trimming cut through the projecting cover margins by means of scissors. This operation is shown in Fig. 3 as being accomplished by means of scissors 20 arranged to cut at a substantial angle to the cut y made by the knife 14 so as to form two oppositely inclined cuts z in each overlapping end portion of the cover at opposite ends of the bevel cut y. The scissors may be readily manipulated to vary the angle of cut as may be desired to provide adequate clearance for the projecting lateral margins of the cover as they are folded back against the respective end surfaces of the heel.

After the trimming cut y has been extended from edge to edge of each of the overlapping portions of the cover, as by means of the inclined cuts z, so as to completely to sever from the cover the waste pieces indicated at w, w' in Fig. 2, these waste pieces are removed, it being necessary to raise somewhat the outer end portion of the cover before being able to remove the

waste piece w' . This raising of the outer end portion of the cover is rendered practicable by the employment of a non-elastic slow-drying adhesive such as rubber cement, inasmuch as the elastic adhesion thus produced between the end portions of the cover may be readily broken when it is desired to remove the waste trimmed from the inner end portion of the cover. Thereafter, the adhesion may be readily re-established by merely pressing the trimmed end portion of the cover back against the heel surface. While the outer end portion of the cover remains in raised position the beveled edges 16 and 18 are coated with non-elastic adhesive such as celluloid cement, by means such as a brush 22, as shown in Fig. 4. Thereafter the raised portion of the cover (indicated at a in Fig. 4) is pressed backwardly against the heel breast and the beveled edge 16 is pressed firmly against the beveled edge 18. The adhesive originally applied to the cover and to the heel will then cause the temporarily raised portion of the cover to adhere to the heel breast while the adhesive applied to the beveled edges 16 and 18 will insure that the beveled edges 16 and 18 will be securely fastened together. Because of the fact that the end portion a of the cover (on which the beveled edge 16 is formed) originally overlapped the opposite end portion of the cover, the portion a will be slightly longer (measured in a direction widthwise of the heel breast) than required to cover that portion of the breast which still remains to be covered. Consequently, in order to insure that the beveled edge 16 will not project beyond the beveled edge 18 but, on the contrary, will exactly register with the edge 18, the cover portion a may be manipulated while being laid, as by means of wiping strokes in the direction of the arrow b in Fig. 4, so as to effect the desired accurate registration of the beveled edge faces 16 and 18 and to press the cover tightly and smoothly against the heel breast surface. Such manipulation of the cover portion a will result in somewhat compressing or consolidating the cover material widthwise of the heel breast, thereby smoothing out the cover and removing any fullness which may be present therein. This action makes allowance for subsequent shrinkage of the cover such as might result in opening up the joint between the meeting edges 16 and 18. It is to be noted that if the beveled trimming cut is made so that its transverse inclination is inwardly away from the edge of the outermost of the overlapping end portions of the cover, as hereinbefore described, it will not be necessary in any case to stretch the end portion of the cover which is finally to be laid in place, so that even if the cover portion a should not be manipulated for the purpose of compressing it widthwise of the heel breast there will be no inherent tendency for the portion a of the cover to pull away from the other end portion thereof. It is desirable that the adhesive employed for coating the beveled edges 16 and 18 will be of non-elastic character which is unaffected by moisture or varying atmospheric conditions, and which consequently will hold the edges permanently and rigidly in place. 75

When a heel cover has been applied as above described, not only will the presence of an objectionable bulge or ridge at the meeting ends of the cover be avoided, but, as shown at 22 in Figs. 5 and 6, a smooth flush joint will be formed between these end portions and one which permanently secures the end portions together and presents a neat and attractive appearance. A joint of this character is particularly well adapted for securing together the ends of both leather and celluloid covers. In the case of celluloid covers it is practicable, by buffing or polishing the surface of the cover adjacent to the joint, entirely to obscure the joint, 90 thus giving the appearance of a jointless cover. 85

Having described my invention, what I claim as new and desire to secure by Letters Patent of the United States: 95

1. That improvement in methods of covering heels which consists in overlapping two portions of a heel covering upon a heel surface to be covered thereby, and cutting diagonally through both of said cover portions while they remain overlapped to form on said cover portions beveled edge faces transversely disposed at the same inclination to the adjacent portion of the heel cover surface. 100
2. That improvement in methods of covering heels which consists in overlapping two portions of a heel covering upon a heel surface to be covered thereby, and cutting through both of said cover portions simultaneously while they remain overlapped to form on said cover portions beveled edge faces lying in the same plane. 110
3. That improvement in methods of covering heels which consists in overlapping two portions of a heel covering upon a heel surface to be covered thereby, and cutting through said overlapped cover portions by a single progressive cutting operation so as to form on said cover portions overlapping beveled edge faces transversely inclined at the same angle to the adjacent portion of the heel cover surface. 115
4. That improvement in methods of covering heels which consists in overlapping two portions of a heel covering upon a heel surface to be covered thereby, and cutting through both of said cover portions while they remain overlapped to form on each cover portion a trimmed edge face trans- 125

versely inclined relatively to the surfaces of said cover portions.

5. That improvement in methods of covering heels which consists in wrapping a cover around a heel, overlapping the opposite end portions of the cover upon the heel and temporarily securing them together by elastic adhesive, trimming the overlapping portions of the cover while they remain overlapped against the heel, breaking the elastic adhesion between said end portions, removing the waste material produced by the trimming operation, and permanently securing the trimmed edges together by non-elastic adhesive.

6. That improvement in methods of covering heels which consists in applying a heel covering to a heel and overlapping adjacent portions of the covering upon one of the lateral surfaces of the heel, trimming the overlapping portions of the covering by a single progressive cutting operation while said portions remain overlapped upon the heel, raising the outermost of said overlapped portions and removing the waste material thereby exposed, replacing said raised portion against the heel surface, and fitting and securing together the trimmed edges.

7. That improvement in methods of covering heels which consists in wrapping a heel covering around a heel, laying one end portion of the covering upon one of the lateral surfaces of the heel, laying the opposite end portion of the covering over said first portion and securing the overlapped portions together by elastic adhesion, trimming the overlapping portions of the covering by a single progressive cutting operation while said portions remain overlapped upon the heel, removing the waste material produced by the trimming operation, and securing the trimmed edges together by non-elastic adhesive.

8. That improvement in methods of covering heels which consists in wrapping a cover around a heel and overlapping the opposite end portions of the cover upon the heel, cutting inwardly through said overlapped margins to bevel them at the same angle, removing the waste produced by the trimming operation, and securing the trimmed margins together with their beveled faces abutting.

9. That improvement in methods of covering heels which consists in wrapping a cover around a heel and overlapping the opposite end portions of the cover upon the heel, cutting inwardly through said overlapped end portions to produce beveled cuts in each portion extending longitudinally heightwise of the heel and sloping transversely inwardly away from the edge of the outermost end portion of the cover, removing the waste material produced by the trimming operation, fitting the trimmed

edges together, and pressing the cover portion having formerly the outermost overlapping margin against the heel to smooth out any fullness therein.

10. That improvement in methods of covering heels which consists in wrapping a cover around a heel and overlapping the opposite end portions of the cover upon the heel, cutting simultaneously through said overlapped margins to bevel them at the same angle, removing the waste produced by the trimming operation, and securing the beveled edges together by celluloid cement.

11. That improvement in methods of covering heels which consists in applying a cover to the rear, side and breast surfaces of a heel and overlapping the end portions of the cover upon the heel breast, cutting through both overlapping cover portions while they remain overlapped against the heel breast to form beveled edges extending each in the same direction heightwise of the heel breast and each having the same angle of bevel, removing the waste material produced by said cutting operation, and securing the said beveled edges together to provide a flush joint.

12. That improvement in methods of covering heels which consists in covering the rear, sides and breast surfaces of a heel with a one-piece cover and overlapping the opposite end portions of the cover upon the heel breast, drawing a knife simultaneously through both said end portions in a direction inwardly from the edge of said outermost portion to bevel the edges of said portions at the same angle, removing the waste material produced by the cutting operation, and uniting said beveled edges.

13. That improvement in methods of covering heels which consists in applying a cover to the rear, side and breast surfaces of a heel and overlapping the opposite end portions of the cover upon the heel breast, cutting through both overlapping cover portions while they remain overlapped against the heel breast to form a beveled edge on each of said portions extending heightwise of the heel breast and inclined widthwise of the heel breast inwardly away from the edge of the outermost of said overlapping cover portions, removing the waste material produced by said cutting operation, and securing said beveled edges together to provide a flush joint.

14. That improvement in methods of covering heels which consists in covering the rear, sides and breast surfaces of a heel with a one-piece cover and overlapping the opposite end portions of the cover upon the heel breast, cutting through both of said end portions of the cover in a plane inclined inwardly away from the edge of the outermost end portion of the cover, removing the waste material produced by the cutting

operation, and uniting said beveled faces to form a flush joint between the end portions of the cover.

15. That improvement in methods of covering heels which consists in applying to the rear, side and breast of a heel a cover having end portions adapted to overlap one another, cutting through both end portions of the cover to produce beveled edges each 10 having the same angle of bevel and extending each in the same direction relatively to the cover, removing the waste material produced by said cutting operation, and securing said beveled edges together with both 15 end portions of the cover against the heel.

16. That improvement in methods of covering heels which consists in adhesively securing a one-piece cover to the rear, side and breast surfaces of a heel, overlapping 20 the opposite end portions of the cover at the heel breast and temporarily securing them together, cutting through both overlapping portions of the cover while they remain overlapped against the heel breast to produce 25 beveled edges lying each in a plane inclined inwardly away from the edge of the outermost of the overlapping cover portions, raising the outermost cover portion, removing the waste material produced by the trimming 30 operation, coating said beveled edges with adhesive, securing said raised portion of the cover to the heel breast, and pressing together said trimmed edges to form a flush joint.

35 In testimony whereof I have signed my name to this specification.
